G. W. SMITH

INGROWN TOENAIL APPLIANCE

Filed Sept. 20, 1920

FIG. 2.

Inventor

G. W. SMITH

By W. J. Fitz Gerald & Co

Attorney

UNITED STATES PATENT OFFICE.

GUY WM. SMITH, OF PAONIA, COLORADO.

INGROWN-TOENAIL APPLIANCE.

Application filed September 20, 1920. Serial No. 411,356.

To all whom it may concern:

Be it known that I, Dr. GUY WM. SMITH, a citizen of the United States, residing at Paonia, in the county of Delta and State of Colorado, have invented certain new and useful Improvements in Ingrown-Toenail Appliances; and I do hereby declare the following to be a full, clear, and exact description of the invention, such as will enable others skilled in the art to which it appertains to make and use the same.

The present invention relates to an appliance for remedying and curing ingrown toe-nails, which, for various reasons grow into the flesh of the toes at the corners of the nails, causing the flesh to become swollen and irritated, and resulting in pain and irritation, especially when the shoe presses the nail down against the flesh.

It is the object of the invention to provide an extremely simple device for application to the ingrown toe-nail and operable for lifting the corners thereof away from the flesh, so as to afford immediate relief from pain and irritation, and to correct the position and form of the nail, and give the flesh an opportunity to heal, and such device being so constructed that it will not interfere with the wearing of hose, and footwear.

A further object is to so construct the device that it is readily adjusted to toe-nails of different sizes or widths with equal facility, and the sections or parts of the device being maintained in their adjusted position when the device is applied, to avoid accidental adjustment or loosening.

With the foregoing and other objects in view, which will be apparent as the description proceeds, the invention resides in the arrangement and construction of parts hereinafter described and claimed, it being understood that changes can be made within the scope of what is claimed, without departing from the spirit of the invention.

The invention is illustrated in the accompanying drawing, wherein:

Figure 1 is a plan view of the device as applied to a toe-nail.

Fig. 2 is a perspective view of the device in its natural position before attachment.

Fig. 3 is a longitudinal section of the device as applied to the toe-nail.

The appliance is constructed of two flat resilient strips or sections 6 and 7 of metal or other suitable material, each of a length less than the width of the toe-nails for which

the appliance is suited, and such strips can be of different lengths for large and small nails, although the device is adjustable within certain limits, for nails of different sizes or widths. The strips 6 and 7 are formed at their opposite ends with hooks 8 to engage around and under the edge of the toe-nail N, near the corners of the nail, and said strips are normally flat, as seen in Fig. 2, and their adjacent end portions overlap each other.

The strips or sections 6 and 7 are slidably connected, for adjusting the device to different lengths for nails of different sizes. Thus, the strip 6 has ears 9 at its side edges adjacent to its inner end bent downwardly and inwardly around and under the edges of the strip 7, and the edges of the strip 7 are similarly provided with ears 10 at the inner end of the strip 7 bent upwardly and inwardly toward one another around and over the edge portions of the strip 6. Thus, each strip has means at its inner end slidably embracing the other strip, whereby the two strips can be slid toward or away from one another to decrease or increase the length of the device to the width of the nail. This adjustment of the device is readily done when the strips are straight, as seen in Fig.

2, and when the strips are bent over the nail and the hooks 8 engaged with the edges of the nail, as seen in Fig. 3, the bending of the strips will cause the strips to bind or grip within the ears or portions 10, thereby preventing the sliding adjustment of the strips in this position, and avoiding accidental adjustment or loosening of the device when applied.

In applying the device the strips are separated sufficiently so that the hooks can be moved across the edges of the toenail. The intermediate portion of the device, which is of double thickness, owing to the overlapping of the strips, is then placed on the toenail between the edges thereof, and this portion of double thickness will be stiffer than the terminal portions. The terminal portions of the strips having the hooks are then sprung toward the edges of the nail, thereby moving the hooks across said edges,

and the strips are then pushed or forced together, to move the hooks under the edges of the nail, while the strips are sprung. In some cases, when the toenail is ingrown to a considerable extent, so that the strips cannot be slid or adjusted while bent, the strips are adjusted while straight to the width of

the nail, and one hook is then engaged under one edge of the nail and the device swung to engage the other hook under the opposite edge of the nail, the device being thus slipped on the nail from the end thereof.

The device occupies very little space over the toe-nail, and will not irritate or chafe the flesh. Owing to the fact that the strips 6 and 7 are sprung or bowed over the nail, 10 they have a tendency to straighten out, thereby lifting the corners of the nail upwardly away from the flesh, and giving relief from the irritation and pain. Furthermore, the corners of the nail are kept in raised position, thereby correcting the shape and growth of the nail, so that it assumes more of a flat shape, and also giving the flesh under the nail an opportunity to heal and become normal, so that when the device is finally removed, 15 no further trouble with the toe-nail will be had. The device being of thin metal, can be worn without interference with the hose and footwear, and, furthermore, will not cause annoyance by contact with the bed

covering when sleeping. The device can be 25 worn for any period of time, until the toe-nail and flesh have been corrected, and is entirely sanitary and will not infect the tissues.

Having thus described the invention, what is claimed as new is:-

An ingrown toenail appliance comprising a pair of resilient strips having their adjacent end portions overlapping and slidably connected for purpose of adjustment and providing an intermediate portion of double 35 thickness to bear on the toenail, the opposite terminals of said strips being adapted to be sprung toward the edges of the nail and having hooks to be engaged under said edges while said opposite terminals are 40 sprung to the edges of the nail.

In testimony whereof I have signed my name to this specification in the presence of two subscribing witnesses.

DR. GUY WM. SMITH.
